UNITED STATES PATENT OFFICE

2,073,623

SUBMERGIBLE PUMP AND TRANSMISSION
UNIT

Charley C. Brown, Ponca City, and Samuel N. Van Wert and Armais Arutunoff, Bartlesville, Okla., assignors to Reda Pump Company, Bartlesville, Okla.

Original application September 15, 1933, Serial No. 689,532. Patent No. 2,032,000 dated February 25, 1936. Divided and this application October 14, 1935, Serial No. 44,948

4 Claims. (Cl. 103—46)

This invention consists in new and useful improvements in mechanism for raising fluid from deep oil and water wells, the present application being a division of our co-pending application 5 Serial No. 689,532, filed Sept. 15, 1933, now Patent No. 2,032,000, February 25, 1936.

One object of this invention is to provide in the novel combination of a pump, submersible electric motor, transmission and lubricating unit disclosed in the parent application, an efficient means for transforming the rotary motion of the vertical shaft of an electric motor, into reciprocating motion of the pump stems.

Another object of our invention is to provide, 15 in a device of this character, means whereby different sizes of plungers or pistons and liners may be used and whereby the changing from one size to another may be accomplished conveniently in the field.

20 A still further object is to provide in a vertical duplex pump for oil wells, an arrangement whereby for a given well size, plungers of a maximum diameter may be employed. In other words, larger plungers may be used than the size normally prescribed by the center distance between 25 the pump stems.

Still another object is to provide an arrangement of cross heads and stationary guides whereby, when it is necessary to unscrew an old 30 plunger and replace it with a new one, the cross heads are prevented from rotating by the stationary guides.

With the above and other objects in view which will appear as the description proceeds, our invention consists in the novel features herein set forth, illustrated in the accompanying drawing and more particularly pointed out in the appended claims.

40 Referring to the drawing in which numerals of like character designate similar parts throughout the several views,

Fig. 1 is an enlarged sectional view of the transmission unit.

Fig. 2 is a transverse sectional view taken on 45 line 2—2 of Fig. 1.

Fig. 3 is a transverse sectional view of the gearing mechanism taken at right angles to Fig. 1, and

Fig. 4 is an enlarged sectional view of the pump 50 unit showing at its lower end the point of connection with the transmission unit.

In the drawing, referring to Figs. 1-3, the numeral 1 represents the upper end of a motor shaft which extends upwardly into the lower portion of a transmission unit 2 and is splined as

5 at 3 to operatively carry a spur gear 4 which, through the medium of planetary gears 5 on pins 6 of a spider 7, rotates a bevel pinion 8, the latter in turn operatively engaging a bevel gear 9 carried on the transverse shaft or axle 10. 5 A gear 11 carried by the axle 10 meshes with an intermediate gear 12 and through it transmits power to a toothed crank shaft gear 13 supported on bearings 14.

The crank shaft gear 13 is formed with disc-like sides 13a as shown in Fig. 1, and is preferably machined out of a solid sphere-like forging, the gear, sides and bearings 14 being integral. This gear is operatively connected by means of connecting rods 15 to cross heads 16 which support the lower extremities of pump stems 17, the latter being connected at their upper ends to hollow plungers 19 by means of suitable adapters 18 as shown in Fig. 3. It will be noted that the distance between the centers of the pump 20 stems 17 is greater than the distance between the centers of the cross heads 16. This arrangement permits the combination in a unit of a given outside diameter, the maximum strength of crank 25 mechanism with plungers of a maximum diameter, a feature of great importance in handling large volumes of fluid.

Each plunger 19 is equipped with a valve 20, preferably of the ball type, at its upper end, and is open to communication with intake passageways 21 in the respective adapters 18. The plungers 19 are reciprocably mounted in a liner 22 in cylinder block 23 which is enclosed in a cylindrical screen-like casing 24. The casing 24 is perforated as at 25 throughout the greater portion of its area and is closed at its upper extremity by a discharge valve plate 26 connected in any suitable manner to a discharge connection 27, the latter being provided with valves 28 and discharge passageways 29 which converge in communication with a central discharge conduit. The lower extremity of the casing 24 is closed by a packing housing 30 having stuffing boxes 31 through which the pump stems 17 reciprocate.

The cylinder block 23 is provided with intake ports 32 at its lower extremity, said ports being located below the perforations 25 in the screen or casing 24, whereby a gas separating action is effected on the fluid entering the screen 24.

The packing housing 30 extends downwardly 50 from the pump unit and is connected by any suitable means to the upper end of the jacket 33 which encloses the gear transmission mechanism heretofore described, said jacket having 55 welded at its upper end a ring 34 and cross head

- guide piece 35 in which the cross heads 16 operate. The cross head pieces 16 are provided with grooves 16a adapted to engage a stationary key piece 36 in the guide 35, whereby the pump stems 17 may be screwed and unscrewed in the cross heads without effecting any torque on the parts below the cross heads.
- The whole transmission mechanism (Fig. 1) is tightly enclosed in the jacket 33 with the cross head guide piece 35, crank shaft gear 13 with its bearings 14 and the other associated gears assembled in a supporting frame made up of two semi-circular sections 37 and 38 which extend longitudinally in the jacket 33. These semi-circular sections 37 and 38 are assembled in the form of a cylinder and are secured at their lower ends to a member 39 which houses a stationary internal gear 40 with which the planetary gears 5 are adapted to cooperate.
- With this structure it will be seen that when the motor shaft 1 rotates, said rotary motion is transformed through the series of gears in the transmission unit to reciprocating motion of the connecting rods 15, which, through the medium of cross heads 16 and pump stems 17, reciprocate the plungers 19 of the pump. The reciprocation of the pump plungers causes fluid to be drawn into the cylindrical casing 24 through the perforations 25 from whence it flows downwardly to the bottom of the cylinder and in through the intake ports 32 located below the lowermost perforation 25 whereby a gas separating action is effected on the fluid being pumped. The fluid then rises through the respective intake passageways 21 at the lower ends of the plungers 19 and enters the space between the ball valves 20 and the standing valves 28, from whence as the plungers reciprocate, it is forced through the converging discharge passageways 29 into the discharge conduit 27.
- It will be noted that the particular arrangement of hollow plungers 19 carrying the traveling valves 20 permits the construction of a pump chamber with a minimum dead space between the traveling valves 20 and the standing valves 28. In other words, it allows the handling of gaseous liquids under a high compression ratio comparable to that of high pressure gas compressors.
- From the foregoing it is believed that the construction and advantages of my invention may be readily understood by those skilled in the art without further description, it being borne in mind that numerous changes may be made in the details disclosed without departing from the spirit of the invention as set out in the following claims.

What we claim and desire to secure by Letters Patent is:—

1. A transmission mechanism for transforming the rotary movement of an electric motor shaft into reciprocating movement for operating a pump, comprising a supporting frame, a housing surrounding said frame, a rotary driving shaft extending axially into one end of said housing, a pair of cross heads reciprocably mounted in suitable guideways provided in the opposite end of said frame, a crank gear in said frame, connecting rods operatively connecting said cross heads with said crank gear, a series of gears operatively connecting said driving shaft with said crank gear, and pump stems eccentrically mounted on said cross heads for operating said pump.

2. Mechanism as claimed in claim 1 wherein said cross heads are provided with oppositely disposed longitudinal grooves, and a fixed key transversely mounted between said cross heads and riding in said grooves, whereby rotation of the cross heads is prevented.

3. In a submersible reciprocating pump unit, an electric motor for driving said unit, a duplex vertical pump including reciprocating plungers, a crank gear mounted in suitable bearings, connecting rods carried by said crank gear, cross heads at the ends of said connecting rods, guide means for said cross heads, means connecting said cross heads with the plungers of said pump with a greater center distance between said plungers than that of the cross heads, to allow the full utilization of the available space for the purpose of large plunger diameter, and means for operatively connecting said crank gear and said motor.

4. A transmission mechanism for transforming the rotary movement of an electric motor shaft into reciprocating movement for operating a pump, comprising a supporting frame, a housing surrounding said frame, a rotary driving shaft extending axially into one end of said housing, a pair of cross heads reciprocably mounted in suitable guideways provided in the opposite end of said frame, a crank gear in said frame, connecting rods operatively connecting said cross heads with said crank gear, a series of gears operatively connecting said driving shaft with said crank gear, and pump stems connected to said cross heads with a greater center distance than that of the cross heads to allow the full utilization of the available space for the purpose of large diameter plunger.
